UNITED STATES PATENT OFFICE

CHARLES H. NORTON, OF PLAINVILLE, CONNECTICUT, ASSIGNOR TO NORTON COMPANY, OF WORCESTER, MASSACHUSETTS, A CORPORATION OF MASSACHUSETTS

LAPPING OR GRINDING MACHINE

Application filed March 14, 1928. Serial No. 261,472.

My invention relates to lapping or grinding machines, and particularly to a machine in which a large number of substantially duplicate pieces of work are treated at the same 5 time.

One type of machine employed for lapping round bodies of work comprises a lower stationary lap, an upper rotatable abrasive wheel or lapping member and a rotary cage therebetween adapted to hold a plurality of pieces of work in operative contact with the lapping members. Such a machine is particularly useful for lapping duplicate pieces of work that are cylindrical in shape or have parallel 10 flat ends. As heretofore constructed and used, such machines have necessitated separating the upper lapping element from the lower lap in order to permit manual replacement of the pieces of work carried in the cage. 15 This has involved a considerable waste of time.

The primary object of my invention is to provide a lapping or a grinding machine of the above described type in which the parts 20 are so constructed and arranged that the work may be loaded in and removed from the cage easily and expeditiously.

With this and other objects in view as will be apparent to one skilled in the art, my invention resides in the combination of parts 25 set forth in the specification and covered by the claims appended hereto.

Referring to the drawings in which like numerals indicate like parts:

30 Fig. 1 is a vertical front elevation partly in section of a simplified form of a lapping machine embodying my invention, the cage being in the work loading position and having parts broken away to more clearly show the 35 construction;

Fig. 2 is a vertical elevation of the machine with the cage in the grinding position;

Fig. 3 is a plan view of the machine showing the cage in the loading position;

40 Fig. 4 is a diagrammatic view of the lap and the work cage showing their relative positions during grinding;

Fig. 5 is a perspective view partly broken away showing the work feeding and removing mechanism;

Fig. 6 is a detail of the work feeding mechanism; and

Fig. 7 is a fragmentary detail of the work cage driving mechanism.

My invention comprises a lapping or a 55 grinding machine having a lower work supporting lap or grinding member and an upper lap or grinding member contacting with the work which may be relatively rotatable or stationary and between which is a rotary 60 cage adapted to hold a plurality of pieces of work in simultaneous contact with both of the lapping or grinding elements. One main feature of my invention contemplates the provision of mechanism which makes it easy to 65 load the cage and to inspect the work without material waste of time. For this purpose, I provide manually controllable means which permits the operator to unload the cage after the lapping operation has gone on for a desired 70 length of time, and thereafter by a further manually controlled device he may load the cage for a new lapping operation without removing the cage from the machine. The unloading may be accomplished by 75 mechanism which releases the pieces of work from the cage, as through a closure in a retaining part of the machine; and the pieces may be loaded into the cage from an overhead magazine arranged to feed the pieces, when 80 desired, into the work carrying portion of the cage.

Various constructions may be utilized for this purpose, but in the embodiment illustrated, the cage is mounted for movement laterally so as to expose its work carrying portion outside of the lapping zone. This may be accomplished by mounting both the cage and the lower lap on a slide, so that they may move out from under the upper lap sufficiently to permit loading the cage.

The embodiment of my invention shown in the drawings comprises a lapping machine for cylindrical work comprising a suitably shaped base 10 having an annular lapping member 11 rotatably mounted in a sleeve 12 on the arm 13 of the upright portion 14 of the base. A plurality of pieces of round work 15 are adapted to be rotatably held in suitably shaped slots in a cage 16 which is rotatably 100

supported above a lap 18 along which the work is adapted to roll and slide during a lapping operation. This lap 18 comprises an annular member mounted on the support 20 which is in turn carried on the slide 22. It will be understood that the laps are suitably shaped depending on the shape of the work, but it will be observed that the laps have parallel faces or that opposed circular lines in their operative faces lie in parallel planes.

The slide 22 is constructed and arranged to slide on suitable flat and V-ways 23 and 24 respectively on the machine base, as clearly illustrated in Fig. 2. The under side of the slide has a rack 25 meshing with a gear 26 which is driven through a shaft 27, and a suitable hand wheel 28 is provided to move the slide into and out of an operative lapping position.

20 The cage 16 may be suitably rotated to cause the work to travel around the faces of the laps, and for this purpose the cage is preferably provided with a downwardly projecting hub 30 which is secured on the post 31. 25 The latter is rotatably mounted in the table 22 and the supporting member 20, as illustrated in Fig. 1, the hub 30 bearing on the table 20 and serving to hold the shaft in position.

30 In order that the cage may be rotated in all positions of the slide, I may utilize the construction illustrated in Figs. 1 and 7, in accordance with which a main driving pulley 35 on the shaft 36 serves to transmit rotative power to two beveled gears 37 and 38 on the shafts 36 and 31 respectively. The gear 37 is slidably keyed to the shaft 36, as shown in Fig. 7, the key 39 riding in the elongated groove 40 of the shaft 36. The shaft 36 is 40 suitably supported in bearings on the bracket 42 suspended from the under side of the slide 22.

The cage 16 may be suitably formed to hold a plurality of work pieces. In the present case, as illustrated diagrammatically in Fig. 4, it has slots or openings 45 therein which are arranged to carry pieces of work with their axes each at an angle to a radial line, so as to accentuate the sliding motion 50 between the work pieces and the laps and so increase the lapping action. It will also be observed that the lap 18 and the path of the work in the cage 16 are eccentric to the grinding wheel or lapping member 11 so 55 that the pieces of work will traverse laterally across the entire width of the lapping member 11 and so uniformly utilize all of the surface thereof.

The lapping member 11 may be made of 60 suitable material, as for example it may be an abrasive wheel made, for example, of ceramic bonded crystalline abrasive grains, or it may be made of cast iron, in which case the lapping material may consist of a loose 65 abrasive powder and a suitable lubricant,

such as oil, which is fed to the work during the lapping operation. The lower lap 18 has been illustrated as made of iron, but it will be understood that various suitable materials may be employed for the purpose.

The lapping member 11 is suitably suspended on a head 50 mounted on the lower end of the spindle 51 which is rotatably and vertically movable in the sleeve 52 carried in the supporting head 12. The sleeve may be keyed to the head to prevent its rotation, and it may be raised and lowered by means of the screw threaded hand wheel 54 mounted on the threads 55 on the sleeve 52. By rotating the hand wheel 54, which has a bearing surface on the upper end of the head 12, the spindle 51 may be raised or lowered to adjust the position of the upper lap relative to the work. The upper lapping member 11 is rotated by means of the pulley 58 fixed to the upper end of the spindle 51 and which is in turn rotated by the driving belt 59 coming from a suitable source of power. If the belt is removed, the upper lapping member 20 will remain stationary, and the lapping operation will be caused by the rotating cage alone.

It will be apparent that during the lapping or grinding operation, the hand wheel 54 may be moved upwardly to the point of letting the upper lap rest freely on the work and descend under the influence of gravity as the work is reduced in diameter. It is also feasible to have the head 50 mounted on a universal joint permitting the head to adjust itself freely to fit the various pieces of work throughout the extent of the cage. It will be understood that the constructional features of the driving head may be suitably modified in accordance with the type of work to be lapped or ground as is well understood by one skilled in the art.

An important feature of this invention involves provision for loading the work carrying cage quickly and easily, and if this is to be done automatically I may employ a magazine which will feed the work pieces one by one into the openings of the cage as the cage revolves beneath the magazine. In order that the work may be discharged automatically I provide a suitably located closure, such as a trap door so located that as the cage revolves over this door the work pieces will automatically fall through this opening and be discharged from the machine.

One embodiment of this invention is shown particularly in Figs. 1, 5 and 6, in accordance with which the magazine carrier comprises spaced walls 60 and 61 suitably supported on a bracket 62 projecting from the machine base. The pieces of work, which are illustrated as cylindrical bodies, may be suitably held in this magazine as by means of a lever 64 having an inwardly projecting arm 125 engaging the lower piece of work in the maga- 130

zine. The arm is held in position beneath the work by means of a spring 65 tending to push outwardly on the upper portion of the lever, as shown in Fig. 6.

5 The closure is shown particularly in Fig. 5, and comprises an opening 70 in the lap 18, which is located at one side of the magazine when the slide had been moved outwardly into the inoperative position. The opening 70 is adapted to be closed by a door 72 having a plane top surface which in the closed position forms a continuation of the lap surface, so that the work will roll over this door without affecting the lapping operation.

15 In order that this trap door 72 may be operated to permit work to fall through the opening as the cage 16 is revolved, it is supported by means of a rod 75 slidably passing upwardly through the slide 22 and the support 20 and pivotally attached to the door. A lever 76 pivotally connected at a central point by the link 77 to the slide 22 makes it feasible to slide the rod 75 up and down and thereby close and open the door. The opening 70 in the lap is enlarged beneath the surface of the lap 18, as clearly shown in Fig. 1, to provide two inwardly projecting shoulders against which the flanged portion 78 of the trap door will engage when pushed upwardly, thereby correctly locating the door when closed. The trap door is pivoted to the rod 75 so that when the rod is drawn to the lowermost position the door will assume the position shown in dotted lines in Fig. 1 in a recess 25 in the opening in the support 20 whereby the work may fall through the opening onto the sliding shelf 80 and so escape from the machine.

The operation of this device will be apparent from the above disclosure. To load the machine the slide 22 is moved outwardly and the latch 64 at the bottom of the magazine is moved so that as the cage 16 revolves, pieces of work will roll successively into the 40 various openings in the cage until it is filled. Then the slide is moved inwardly by means of the hand wheel 28 until the pieces of work are properly located beneath the upper lapping element 11. Then the hand wheel 54 is turned to lower the upper lap into contact with the work and permit it to rest freely thereon during the lapping operation. The lapping member 11 and the cage 16 are rotated at suitable slow speeds until the lapping operation has been accomplished. Then the lapping member 11 is raised slightly to release the work and the slide 22 is moved outwardly. Thereafter the trap door 72 is opened by means of the operating lever 76 and the 55 pieces of work are permitted to fall out of the slot of the cage 16 as the cage continues to revolve.

It will be understood that the term "lapping" as used in the claims and specification 60 is to be interpreted broadly as covering a

grinding operation, since a lapping machine embodying the principles of my invention may be used either to polish or lap the work or to remove a considerable amount of stock as determined by the nature of the lapping elements and the method and time involved in carrying on the operation. Also it is to be understood that the cage or either or both of the laps may be given a compound movement instead of a simple rotary motion, as herein described, as will be understood by one skilled in the art, to accomplish the lapping or grinding operation.

Having thus described my invention, what I claim as new and desire to secure by Letters Patent is:

1. A lapping machine comprising opposed laps and a work carrying cage therebetween which are relatively movable to lap a plurality of work pieces simultaneously, a slide supporting the lower lap and cage, and means for moving the slide to remove a portion of the cage from beneath the upper lap and permit ready loading of the same.

2. A lapping machine comprising a base, opposed laps and a work carrying cage therebetween which are relatively movable to lap a plurality of work pieces simultaneously, a slide carrying the lower lap and the cage, means to move the slide, a driving shaft on the base, a driven shaft on the slide, and connections between the shafts permitting rotation of the driven shaft for various positions of the slide.

3. A lapping machine comprising opposed laps and a work carrying cage therebetween which are relatively movable to lap a plurality of work pieces simultaneously, means to move the cage laterally to a non-lapping position and expose its work carrying portion outside of the lapping zone and means associated therewith for automatically filling the cage with work pieces.

4. A lapping machine comprising opposed laps and a work carrying cage therebetween which are relatively movable to lap a plurality of work pieces simultaneously, means to move the cage laterally to an inoperative position and expose its work carrying portion outside of the lapping zone, and means including a magazine for work pieces arranged to fill the cage when in such inoperative position.

5. A lapping machine comprising two opposed laps, a work carrying cage therebetween which has openings for a plurality of work pieces, means to revolve one of said members to lap a multiplicity of work pieces at the same time, manually controlled mechanism to remove the work pieces from the cage when desired, and means for automatically loading the cage.

6. A lapping machine comprising two opposed laps, a work cage therebetween having provisions for carrying a plurality of work pieces, means to move one of said members to

- lap the work, means to move the cage laterally from its operative lapping position and means for unloading and loading the cage in such in-operative position.
7. A lapping machine comprising two laps having continuous faces in which opposed circular lines in their operative faces lie in parallel planes, a rotatable work cage therebetween having provisions for carrying a plurality of work pieces in spaced relation adjacent to its periphery, means for rotating the cage and one of the laps so as to lap all of the pieces simultaneously to the same size, and manually controlled means to load the cage after the lapping operation has been completed.
8. A lapping machine comprising two opposed lapping elements and a rotatable work carrier therebetween which are relatively rotatable to lap the work, said carrier being arranged to rotate and hold several pieces of the work between the laps during an indefinite rotative period so as to lap a set of pieces to duplicate sizes, and means acting prior to the lapping operation for filling the carrier with the pieces of work without removing it from the machine.
9. A lapping machine comprising two opposed laps, a work carrier therebetween arranged to rotate and hold a plurality of work pieces in lapping contact with both laps for an indefinite rotative period, and means for automatically loading the carrier without removing it from the machine.
10. A lapping machine comprising two opposed laps having opposed annular lapping faces, a carrier for a plurality of work pieces mounted eccentrically relative to one of said laps and arranged to hold all of the work pieces in lapping contact therewith while it rotates through an indefinite period, and means for loading the carrier after the completion of the operation of lapping said work pieces.
11. A lapping machine comprising two opposed laps and a rotatable work carrying cage therebetween which are relatively movable to lap a plurality of work pieces, a support for the cage movable laterally to locate the cage in a non-lapping and loading position, a drive shaft, fixed bearings therefor, and connections from said shaft to rotate the cage continuously and give a lapping motion thereto when in an operative position between the laps.
12. A lapping machine comprising two lapping elements having opposed faces lying in parallel planes and a rotatable work cage interposed therebetween, means to cause a relative rotation between said members, said cage being arranged to hold a plurality of work pieces in lapping engagement with the opposed laps for an indefinite period of cage rotation, means for moving the cage laterally so as to expose work pieces therein and man-
- ually controllable means to reload the work cage without removing it from the machine.
13. A lapping machine comprising two opposed relatively rotatable laps and a rotatable work cage therebetween which has openings adjacent to its periphery for a plurality of work pieces, means to positively and continuously rotate the work cage and simultaneously lap all of the work pieces within the cage for an indefinite period of time and means to automatically discharge the work pieces successively from the rotating cage whenever desired.
14. A lapping machine comprising two opposed relatively rotatable laps and a rotatable work cage therebetween which has openings therein to receive a plurality of work pieces, means to positively rotate one of the laps, means to positively and continuously rotate the work cage and simultaneously lap all of the work pieces therein to the same size for an indefinite period of time and manually controlled mechanism to remove all of the work pieces from the cage during the rotation of the cage.
- Signed at Plainville, Connecticut, this 10th day of March 1928.
- CHARLES H. NORTON.
